Jack Singler
ATTORNEY

UNITED STATES PATENT OFFICE.

SMITH A. HOGE, OF RICES LANDING, PENNSYLVANIA.

RAIL JOINT.

Application filed April 23, 1923. Serial No. 633,993.

To all whom it may concern:

Be it known that I, SMITH A. HOGE, a citizen of the United States, residing at Rices Landing, in the county of Greene and State of Pennsylvania, have invented certain new and useful Improvements in Rail Joints, of which the following is a specification.

This invention relates to certain improvements in rail joints, and important objects thereof are to provide a joint of the type stated, embodying novel means for joining the rails together; which will interlock with the ends of the rails to assure their alignment; which will lock adjacent rails against longitudinal movement; which may be readily and conveniently attached in position to the rails, and which may be incorporated in a tie element to prevent spreading of the rails.

Further objects of the invention are to provide a rail joint of the class described, which is simple in its construction and arrangement, strong, durable and efficient in its use, positive in its action, and comparatively inexpensive to manufacture.

With the foregoing and other objects in view, the invention consists of the novel construction, combination and arrangement of parts herein specifically described, and illustrated in the accompanying drawings, wherein is shown an embodiment of the invention, but it is to be understood that changes, variations and modifications can be resorted to which come within the scope of the claim hereunto appended.

In the drawing wherein like reference characters denote corresponding parts throughout the several views:—

Figure 1 is a perspective transverse sectional view of my improved rail joint attached to a rail.

Figure 2 is a perspective view of the base member.

Figure 3 is a perspective view of the fish plate.

Figure 4 is a perspective view of the rail having a serrated flange to adapt it for use in connection with my improved joint.

Figure 5 is a top plan view illustrating the adaptation of my improved device to provide a tie element.

Referring in detail to the drawing 1 denotes a base plate formed integrally with a pair of spaced parallel extending lugs 2 and 3, respectively. The base plate 1 is

preferably rectangular in contour and is provided with a plurality of apertures 4 adapted for the passage of spikes for securing the base plate to a rail road tie of the usual construction.

Each of the lugs 2 and 3 extends throughout the width of the base plate 1 and has its inner face formed with a respective longitudinally disposed groove 5, 6, for the purpose hereinafter referred to.

The lower portion of the inner face of the lug 2, providing the lower wall of its groove 5, is formed to constitute a toothed or serrated edge 7, while the corresponding portion 7' of the inner face of the lug 3 is straight or on an even plane throughout.

Each of the rails 8, adapted to be connected by my improved rail joint, has the end portion of one side of its flange 9 constructed to provide a serrated edge 10, which latter engages in the corresponding edge 7 on the inner face of the lug 2 when the rail 8 is mounted on the base plate 1. The distance between the lug portions 7 and 7' is commensurate to the width of the rail flange 9.

In making rail connections, the adjoining ends of the rails 8 are positioned on the base plate 1 so that each extends one-half thereacross. It will here be noted that the serrated edges 10 of the adjacent rail flanges 9, and the interlocking serrated edge 7 of the lug 2 are preferably disposed to position them on the outer side of the rail 8. This arrangement, for obvious reasons, facilitates the laying of the rails 8, but the serrated edges of the rail flanges and lug may be disposed to position same at either side of the rail 8 to best meet conditions found in practice.

When the ends of the rails 8 have been placed in position on the base 1 as above described, they are securely clamped to the base 1 by means of a pair of fish plates 11, one of which is positioned at each side of the rail 8. Each of the fish plates 11 is formed with a plurality of perforations 12', provided for the passage of the securing bolts 13.

Each of the fish plates 11 is formed with an angularly disposed portion 12, the toe of which engages in the groove 5, and 6, of respective lugs 2 and 3, as clearly indicated at 14 in Figure 1, of the drawing. When the fish plates 11 are drawn against the web of the rail by means of the bolts 13, which

extend through the apertures 15 in the rail ends, and the nuts 16, the angularly disposed portions 12 of the fish plates 11, due to their connection in the respective grooves 5 and 6 of the lugs 2 and 3, will engage the rail flange 9 and securely lock the conjoining rail ends against movement on the base plate 1.

The interlocking of the serrated edge 7 of the lug 2 with the serrated flange edges 10 of adjoining rails 8, together with the attachment of the fish plates 11 by the bolts 13 will provide a substantial and well supported rail union, which may be quickly and conveniently fixed in position upon the rails 8.

Figure 5, of the drawing, illustrates the application of my improved device to provide a tie element to also prevent the spreading of the rails. In this construction, an elongated base 17 is provided, having each end thereof constructed to permit of the rail attachment thereto in a manner identical to that herein before described. Each end of the base 17 is formed with a pair of lugs 18, and one of each pair of lugs is provided with a serrated edge 19 on its inner face to engage the flanges of the rails 8.

In railroad construction the parallel extending rails are preferably arranged in a staggered relation with respect to each other,

that is, the end of one rail extends to about the center of the adjacent parallel rail. Owing to this arrangement of the rails, the use of my improved device as a tie element would necessitate the forming of a serrated edge 20 on that portion of the rail directly opposed to a rail joint on the parallel rails.

By the use of the elongated base 17 and associated parts engaging both rails of the track, as above described, a tie element is established which will prevent liability of rail spreading and in consequence reduce accidents from such cause to a minimum.

What I claim is:—

The combination with a pair of rail ends to be connected and having serrated flange edges, of a rail joint comprising a base plate formed with a pair of spaced lugs, each of said lugs provided with a longitudinally extending groove on its inner face, a fish plate 50 engaging in each of said grooves for clamping said rail ends to said base plate, the inner face of the outer positioned lug below the groove therein being formed to provide a serrated edge adapted to interlock with serrated flange edges, substantially as described and for the purpose set forth.

In testimony whereof I affix my signature.

SMITH A. HOGE.
